E. J. O'LEARY.
HAND HOLE COVER.
APPLICATION FILED OCT. 24, 1910.

1,006,263.

Patented Oct. 17, 1911.

UNITED STATES PATENT OFFICE.

EDWARD J. O'LEARY, OF SAN FRANCISCO, CALIFORNIA, ASSIGNOR TO RISDON IRON AND LOCOMOTIVE WORKS, OF SAN FRANCISCO, CALIFORNIA, A CORPORATION OF CALIFORNIA.

HAND-HOLE COVER.

1,006,263.

Specification of Letters Patent. Patented Oct. 17, 1911.

Application filed October 24, 1910. Serial No. 588,625.

To all whom it may concern:

Be it known that I, EDWARD J. O'LEARY, citizen of the United States, residing at the city and county of San Francisco and State of California, have invented new and useful Improvements in Hand-Hole Covers, of which the following is a specification.

This invention relates to plates and guards for closing hand-holes and the like in boilers, 10 and particularly pertains to improvements therein.

It is the object of this invention to provide a hand-hole plate which is free from seams or joints on its inner face so as to 15 prevent possible leakage at the juncture of the plate and stem.

Another object is to provide a hand-hole plate which is strong, durable, light in weight, simple in construction, and of few 20 parts, and which may be readily removed and applied.

A further object is to provide a hand-hole plate which is particularly adapted to be formed of steel by the drop-forging process.

25 The invention consists of the parts and construction and combination of parts as hereinafter more fully described and claimed, having reference to the accompanying drawings, in which—

30 Figure 1 is a vertical section of the invention as applied. Fig. 2 is a perspective view of the guard illustrating the manner of applying the invention to a hand-hole. Fig. 3 is a view in elevation of the head portion of the stem. Fig. 4 is a sectional view showing 35 the method of manufacture. Fig. 5 is a section on X—X, Fig. 3. Fig. 6 is a plan view of the head portion of the same.

In the drawings, A, represents my improved hand-hole plate or cover which is 40 preferably made of soft steel and formed with a bead flange 2 on its inner face which flange is adapted to extend into and fit snug with the side walls of hole 3 in the boiler head 4. The plate A is provided with a stem 5 by a drop-forging process as will be later described; the stem 5 extending centrally at right angles to the inner face of the plate A so as to project some distance through the 45 hole 3 and beyond the inner wall of the plate 4 to permit the cover plate A to be secured in place as follows:—The outer extended portion of the stem 5 is threaded at 6 to receive a nut 7, the stem 5 being formed of

mild steel suitable for threading. A cap or 55 washer 8 fits over the stem and seats around and covers the hole 3, the nut screwing down on this washer and serving to draw the cover plate A tight against the boiler head and 60 form a tight joint.

The important feature of the invention is the way in which the stem is secured to the plate A. Oppositely disposed indentations 9 are formed on the stem 5 at a point near its inner end, to provide grooves or 65 channels on each side of the stem into which is forged a portion of the flange steel plate A. The grooves or channels 9 are formed by pressure or stamping, which squeezes the displaced metal outward to produce the narrower shoulders or ridges 9' on the sides of stem 5 between the ends of the indentations or grooves 9: see Figs. 3—5. This feature of construction is important inasmuch as the sectional area of the stem 5 (see Fig. 5) at 70 this point will remain equal to the cylindrical part of the stem, thus retaining the full tensile strength of the stem 5 throughout its length and not weakening the stem as would be the case were the grooves 9 formed 75 by cutting away and removing the metal. The end of the stem 5 adjacent the grooves 9 is flared outwardly to form a conical or wedge-shaped head 10.

The hand-hole plate A is formed upon 85 the stem 5 in the following manner:—The stem 5, previously shaped with the grooves 9 and shoulders 9' and head 10 as above described, is inserted in a centrally disposed bore in a suitable die 11, as shown in Fig. 4, 90 the grooves 9, shoulders 9' and head 10 projecting above the upper face of the die. The die 11 is mounted in a mold-casing 12 and both are supported upon an anvil 13. The metal of which the plate A is to be made, 95 preferably soft steel, formed in a plain sheet blank as shown at 14, having approximately the cubic content of the completed plate A, is heated to a white heat and placed in the mold 12 on top of the pin 5, as shown. A 100 stamp 15 is then inserted in the mold casing 12 above the heated metal blank 14 and is subjected to several heavy blows from a forge-hammer which drives the stamp upon the blank 14 and forces the hot metal around 105 the head of the stem 5 and into the recesses 9 and under the shoulders 9', in close contact therewith. The underside of the stamp 15

is so recessed at 16 as to form a thickness of metal completely around and over the end of the stem 5, and the die 11 is grooved at 16 on its upper face to form the flange 2 on the inner face of the completed plate A. The plate A and its stem 5 after being removed from the die and mold are plunged into water which cools the heated plate and shrinks it tightly upon the stem 5, the latter 10 being cold when placed in the die 11.

In the application of the invention, the hand-hole plate A is placed over the hole 3 with the flange 2 projecting therein; a gasket 17 of any suitable description being inserted 15 between the inner face of the plate A outside the flange 2 and the plate 4 adjacent the opening 3. The dish-shaped washer 8 which is preferably formed of drop-forged steel is then placed over the threaded end of 20 the stem 5 so that the rim of the washer will contact the outer face of the plate 4 outside of the hole 3. The nut 7 is then threaded on the stem 5 and screwed against the washer so as to draw the hand-hole plate 8 and 25 gasket 17 tight against the face of the plate 4. As a means for preventing the plate A and stem 5 from turning when tightening or loosening the nut 7, a transverse slot 18 is formed in the end of the stem 5 in which a 30 tool 19 of any suitable description may be inserted as shown in Fig. 2, by which the stem 5 may be held rigid against turning. The plate A may be shaped to conform to 35 hand-holes of any form such for example as round and oval, and may be of any desired size.

By the foregoing construction it will be seen that the fulling of the stem to produce the grooves 9 and shoulders 9' forms 40 an expanded head for the bolt and the cross sectional area of the bolt is not reduced at any point in its length. Then, by swaging the plate on to the stem and expanding the material of the plate into the grooves and 45 around the shoulders completely surrounds the head and produces a plate of maximum strength and efficiency.

Having thus described my invention, what I claim and desire to secure by Letters Patent is—

1. A hand-hole plate with a cylindrical stem rigidly mounted therein, said stem having opposed indentations formed near its inner end, ridges on the stem between the 55 ends of the indentations, the sectional area of the stem through the indentations and ridges being substantially equal that of the cylindrical portion of the stem, and a frusto-

conoidal head on the stem adjacent said indentations and ridges.

2. A hand-hole plate with a cylindrical stem rigidly mounted therein, said stem having opposed indentations formed near its inner end, ridges on the stem between the ends of the indentations, the sectional area 65 of the stem through the indentations and ridges being substantially equal that of the cylindrical portion of the stem, and a frusto-conoidal head on the stem adjacent said indentations and ridges, said hand-hole plate 70 having a recess formed therein adapted to receive the head and the metal of the plate surrounding said recess adapted to be embedded around said head, indentations and ridges.

3. A hand-hole plate with a cylindrical stem rigidly mounted therein, said stem having opposed indentations formed near its inner end, ridges on the stem between the ends of the indentations, the sectional area 80 of the stem through the indentations and ridges being substantially equal that of the cylindrical portion of the stem, and a frusto-conoidal head on the stem adjacent said indentations and ridges, screw threads on the 85 outer end of the stem to receive a nut, and means on the outer end of the stem for holding the latter to prevent its turning when the nut is being screwed on.

4. A hand-hole plate with a cylindrical 90 stem rigidly mounted therein, said stem having opposed indentations formed near its inner end, ridges on the stem between the ends of the indentations, the sectional area of the stem through the indentations and 95 ridges being substantially equal that of the cylindrical portion of the stem, and a frusto-conoidal head on the stem adjacent said indentations and ridges, screw threads on the outer end of the stem, to receive a nut, and 100 means on the outer end of the stem for holding the latter to prevent its turning when the nut is being screwed on, said hand-hole plate having a recess formed therein adapted to receive the head and the metal of the plate 105 surrounding said recess adapted to be embedded around said head, indentations and ridges.

In testimony whereof I have hereunto set my hand in the presence of two subscribing 110 witnesses.

EDWARD J. O'LEARY.
